UNITED STATES PATENT OFFICE.

JOSEPH E. CULVER, OF JERSEY CITY, NEW JERSEY.

GENERATOR AND MOTOR.

SPECIFICATION forming part of Letters Patent No. 226,040, dated March 30, 1880.

Application filed June 5, 1879.

To all whom it may concern:

Be it known that I, JOSEPH E. CULVER, M. D., of Jersey City, in the county of Hudson and State of New Jersey, have invented a new 5 and Improved Generator and Motor, of which the following is a specification.

The object of my invention is to utilize for motive power all the force developed from the combustion of fuel, not only all that calorific 10 which can be transferred into steam in the boiler, but also all that usually escapes with the heated and expanded gases or products of combustion through the chimney.

My invention consists in a furnace, boiler, 15 and atmospheric engine combined, and operated as hereinafter set forth.

The furnace may consist of any ordinary fuel-burning apparatus with one or more draft-flues, as preferred, and arranged as desired; 20 but I prefer to place the furnace within the boiler and surrounded by the water for better economy of heat, the flues also being partly submerged in and extending through the water in the boiler and discharging into the steam-space. 25

The boiler may be of any desired size, shape, or pattern, and constructed of any suitable material having sufficient strength and capacity to contain the requisite quantity of water, together with the furnace-flues and the mingled steam and products of combustion, which in this motor exert no pressure above 30 that of the atmosphere.

The engine consists of a cylinder, a steam-inlet pipe connecting the steam-space of the boiler with the cylinder at or near the head, and furnished with a cut-off which shall open as the piston begins to rise and close just before completion of the upstroke, and also an 35 exhaust-pipe and attached pump to withdraw from the cylinder the water and gases after every condensation, and also an injector of cold water into the cylinder to effect the condensation, and thereby cause the return stroke of 40 the piston.

There may be one cylinder only or two conjoined, or a greater number, acting either separately or conjointly, attached to and supplied from the same boiler, as may be desired, 45 provided the capacity of the cylinder or the joint capacity of all employed be great enough

to utilize or condense economically the mixed steam and gases as rapidly as they are evolved in the boiler; but any known modification of a condensing or low-pressure engine can be 55 adapted to the use of such mixture of gases and steam as herein described.

My invention is illustrated in the accompanying drawings, wherein Figure 1 is a vertical section, and Fig. 2 a horizontal section, of 60 a generator and motor adapted for carrying out the invention.

Similar letters of reference indicate corresponding parts.

A is the generator, constructed of light boiler-iron, in a circular form, and containing within it at one side a cylindrical fire-box, B. The fire-box B opens through the top of the generator, and the opening is provided with a cover, a, of any desired character, that can be 70 closed tightly, which cover is only to be removed when fuel is supplied.

The fire-box is provided with a grate, b, below which is the ash-pit, that is provided with an opening, c, through the front of the generator and a door in the opening to regulate the draft.

Within the main shell of the generator is fitted a coil or flue, d, of pipes, that extend throughout the water-space, with one end connected to the discharge-opening e of the fire-box and the other end opening within the shell above the water-line.

Upon the top of the shell A a vertical pipe, f, is connected, which pipe is fitted with a 85 cock or valve, g, that may be opened to permit the escape of the products of combustion or closed to retain them with the steam in the generator.

The operation of these parts is as follows: 90 The generator is to be filled with water up to the dotted line, and a fire kindled on the grate b, with the valve g of pipe f open to allow of draft. When the fire is well under way and the water heated, or even before the water is 95 heated, the valve g is to be closed, and thereafter the products of combustion discharge into the steam-space, out of which they are taken to the engine-cylinders by pipes arranged in any desired manner. The working 100 of the engine by emptying the steam-space continually creates and regulates the draft,

causing at all times just the requisite influx of atmospheric air to the fire. As soon as steam is generated it rises and mingles with the products of combustion and passes with them to the engine-cylinders.

I have shown cylinders C C' with piston-rods connected to a beam, *h*, to obtain alternate movement of the pistons, and with pipes passing from the generator to each cylinder beneath the piston-heads. There are to be suitable valves and connections for cutting off the supply-pipes at the proper times, and the cylinders are to be provided with water-jackets, or fitted so that a jet of water can be injected for condensing the vapors and gases in the cylinders. One piston being raised and the other down, the gases and vapors from the generator enter the cylinder beneath the raised piston-head until the cut-off is operated, when the exhaust of that cylinder is opened and a jet of water injected to condense the vapors and cause the descent of the piston by atmospheric pressure. This movement raises the other piston, and the operation is repeated in the other cylinder. This action will keep up the draft of the fire.

I do not limit myself to any special arrangement of the cylinders, cut-off, and condensing apparatus.

I am aware that engines have been driven by heated air injected into the cylinder and then condensed; also, that the products of combustion from boiler-furnaces have been discharged into the boiler, and the draft maintained by a pressure-blower.

I use the steam and products of combustion in an expanded state under ordinary atmospheric pressure, which mixture may be readily and rapidly condensed, and will not burn out the cylinders and packings.

The pressure within the steam-space will never exceed the external pressure of the atmosphere. There is always open communication to the outer air by the flues and fire-box, and as the steam-space is exhausted by the cylinders the requisite quantity of fresh air is drawn through the fire to supply the deficiency and maintain the equilibrium.

The water in the cylinders after injection acts to lubricate the cylinders.

To prevent waste of heat and loss of power by radiation, convection, &c., the pipes conveying the heated gases and steam should be jacketed with suitable non-conducting material, as should also the entire surface of the boiler.

Having thus described my invention, I claim as new and desire to secure by Letters Patent—

1. The generator A, fitted with the interior fire-box, B, and serpentine flue *d*, said flue being connected to the fire-box and discharging within the steam-space of the generator under atmospheric pressure, out of which, through suitable steam-pipes, the cylinders C C' are supplied, when all are arranged substantially as and for the purpose specified.

2. As an improved motive-power apparatus, a generator of steam wherein the products of combustion are discharged into the steam-space, and with the steam held in an expanded state at atmospheric pressure, combined with cylinders, pistons, and condensing apparatus, whereby the expanded gases are utilized, substantially as described and shown.

JOSEPH E. CULVER.
